CARTON HAVING A DISPENSING FACILITY,
AND CARTON BLANK THEREFOR
George Arlington Moore, New York, N.Y.
(910 Lake Shore Drive, Chicago, Ill.)
Filed Feb. 21, 1963, Ser. No. 260,224
4 Claims. (Cl. 229—17)

This invention relates generally to cartons, and has particular reference to a carton, and to a carton blank of which the carton may be formed, wherein a dispensing facility is provided in an unusually simple, inexpensive, and efficient manner.

The invention relates more particularly to a novel container construction having a permanently sealed flat end closure affording a tight sift-proof condition, and provided at the same time with a dispensing aperture of improved character in an adjacent wall that can be repeatedly uncovered and re-covered without impairment of the end wall securement. The aperture is provided with a novel sub-closure flap that is an integral part of the initial single blank of foldable sheet from which the carton can be set up.

The carton blank can be manufactured, handled and set up with conventional equipment and substantially in accordance with conventional techniques, and the filling and sealing of the set-up carton can be carried out substantially in similar fashion.

An efficient sift-proof carton formed of paperboard material has been sought for many years and is currently a topic of research and development programs in many branches of the container making industry. Those skilled in the art know that such a container must have a leak-proof construction in order to eliminate the undesirable costly necessity for use of augmenting sheet material such as inner liners, bag inserts and/or overwraps. Secondly, such a container, to be efficient, must embody an adequate dispenser facility that can be easily opened without damage in order that it may be tightly re-closed. It is an object of this invention to provide an improved container of the class described, adapted for the efficient distribution of such products as dried milk, confectionery sugar, cake mixes, pharmaceutical powders, dehydrated soups and other hygroscopic commodities.

To this end, it is a primary object of the invention to provide a sift-proof container that eliminates the use of inner lining and overwrap materials and has a novel dispenser facility formed as an integral part of a single carton blank and brought into being during the closing and sealing of an end of the container.

Another object of the invention is to provide novel means for finger manipulation to open the dispenser facility without impairing its subsequent usefulness so that the dispenser may be reclosed in tightly retained condition.

A further object of the invention is to provide a flat end closure which is permanently sealed and remains so, independent of the integrally-formed dispenser sub-closure construction.

The above and other objects with attendant advantages are attained by this invention, a particular embodiment of which I have illustrated in the accompanying drawings. It is to be expressly understood, however, that these drawings are intended for the purpose of illustration only, and are not to be taken as a definition of the limits of the invention, reference being had for this purpose to the appended claims.

In the drawings, wherein similar reference characters refer to similar parts throughout the views shown:

FIG. 1 is a partial plan view of a container-forming blank embodying the features of the invention;

FIG. 2 is a partial view in perspective of a step in the

2

process of setting up a carton formed of the blank of FIG. 1;

FIG. 3 is a partial side elevation of the container with sections thereof broken away and showing in cross-section the progressive steps taken in completing the setting up of the end closure and the dispenser facility;

FIG. 4 is a partial perspective view of the completed container, its flat end closure and dispensing closure facility conjointly formed and sealed;

10 FIG. 5 is a fragmentary view of the container in side elevation, showing it in a tilted position after being opened for dispensing purposes;

FIG. 6 is a fragmentary view of the container, showing the step taken in re-closing the dispenser aperture;

15 FIG. 7 is a partial plan view of a modified carton blank;

FIG. 8 is a partial perspective view of the container formed of the modified blank of FIG. 7; and

FIG. 9 is a similar view of the completed container, showing its dispenser opened for dispensing purposes.

20 An embodiment of the invention is illustrated primarily as being adapted to the folding carton-type container. The improved blank as illustrated is adapted to form an improved container by novel method steps that eliminate the use of conventional paste fountain equipment and the complicated apparatus conventionally utilized for inner lining and overwrapping cartons.

The blank 4 of the present invention may be made of any desired quality of foldable sheet material. Primarily, paperboard of suitable thickness may be processed in sheet 30 or roll form into blanks by conventional practice; the material being printed, adhesive being applied in predetermined patterns, and pattern lustre overcoat being applied over the printing, all in usual manner. The blanks are then cut and creased into the special form illustrated.

35 The blank 4 is cut and creased to form four side wall panels arranged in opposing pairs. More particularly, the blank 4 is composed of hinged front, rear and side panels 5, 6, 7 and 8, separated by the longitudinal hinge lines 9. The panel 5 has a marginal connection portion 10 projecting outwardly at its outer boundary. The side wall panels 6 and 8 are each provided with end edges defined by the aligned crease lines 11; the panel 5 has its end edge defined by crease line 12; and the panel 7 has its end edge defined by crease line 13. The line 12 is spaced upwardly two

40 thicknesses of blank material above its adjacent line 11 and line 13 is spaced upwardly three thicknesses of blank material above the adjacent line 11. The panel 5 is provided with a foldable end closure panel 14 coated on both surfaces inside and out with a dry activatable adhesive *a*.

45 This may be, selectively, a suitable hot-melt resin applied thereupon by knurled coating rolls. The panel 6 of the blank is provided with an aperture 15 having a peaked top edge for a purpose hereinafter to be described, the apex pointing upward toward the adjacent end edge of the panel

50 6. A U-shaped slit 16 is provided below the bottom edge of the aperture 15.

The panel 6 is also provided with a foldable closure forming element 17 projected outwardly from crease line 11. This element is provided with two additional crease lines 18 and 19. The lines 11, 18 and 19 are spaced apart substantially by equal distances and are parallel.

60 The upper portion of the panel 17 is provided with a pair of spaced perforated or otherwise weakened lines 20 extending vertically from the crease line 19 to the end 65 of the panel. Each line 20 is spaced inwardly of the cut side edges 21 of the element and the resultant border space therebetween is coated with a dry activatable adhesive *b* that extends the full length of the panel.

The pattern-applied overcoat gloss material on the blank avoids these marginal areas as well as their counterparts 22 on the panel 6.

70 The outer edge of the element 17 is provided with a

foldable tab portion 23 having a base crease line 24 and slit side edges.

The panel 7 is provided with a secondary foldable end wall panel 25.

The panel 8 is provided with a foldable tuck forming element 26 having a central crease line 18 parallel to the crease line 11. The marginal parts of the element 26 are coated with the adhesive b.

It is to be noted that the shape of the aperture 15 can be modified in any desired manner to suit the dispensing of different products. For example, perforated cut holes may be useful for such products as flour or condiments. The invention also contemplates the blank being provided with an interior surface faced with any desired plastic film such as polyethylene, polypropylene, or other thermoplastic coating material. In such case, the foldable element 14 of the blank need not be separately coated on the inside.

The bottom end of the blank 4 may be provided with the same basic foldable closure forming elements minus the dispenser facility, the crease line 19 in the element 17 becoming a cut end edge.

The blank 4 may be folded and seamed in set-up condition by conventional carton folding machines. The folded blank then appears in the form shown at 27 in FIG. 2. The top end closure is then formed by first flexing the pair of tuck plies e and f to form a two-ply tuck or seating ledge. The plies are folded inwardly along crease line 18 at the same time the lower ply e of each ledge is folded inward on the folding line 11 while the upper ply f turns outwardly into superposed relation to the lower ply e as shown in FIG. 3. The end-wall panel 14 is then folded on its hinge line 12 to bring its resinous coated inner surface upon the up-faced plies f of the two-ply tucks or ledges. While the panel 14 is retained in its folded position to compress the resistant superimposed ledges, the panel portion 17 is folded downwardly upon the corresponding exterior surface of the side wall 6 as shown by dotted lines and arrow in FIG. 3. Accordingly, the adhesive b on the element 17 is brought into contact with the exterior surface of the side wall 6, and the panel portion between the lines of weakness 20 closes the aperture 15. The end-wall panel 25 is then folded on its hinge line 13 onto the exterior coated surface of the panel 14. At this moment heat and pressure may be applied simultaneously upon the exterior surface of the upper margins of the opposing side walls 6 and 8 upon the folded panel 17, and upon the last folded panel 25, thereby activating the adhesives a and b and sealing the closures in a manner to render the container sift-proof.

The completed structure is illustrated in FIG. 4 showing a permanently sealed flat end closure combined with a built-in and sealed dispenser closure. The perforated lines 20 of the closure panel 17 keep it flatly engaged over the aperture 15. The outer bonded marginal portions b are permanently secured upon the side wall 6. Should it be desired, the seal of the closure over the aperture can be reinforced by adding a band of the adhesive b across the panel 17 as illustrated by the stippled lines 28 (FIG. 2).

It is to be noted that because of the peaked shape of the top edge of the aperture 15, distortion or bulging of the side wall adjacent to this edge is avoided when folding the adjacent tuck along its hinge line 11 as shown in FIGS. 2 and 3. The hinge line 19 of the closure panel 17 is firmly secured in straight alignment and reinforcement by the bonded sections of the compressed superposed plies e and f of the seating ledges. Moreover, the end edges 21 of the superposed margins e and f are firmly abutted against the interior surfaces of the opposing front and rear walls 5 and 7 which further reinforces and rigidifies the closure flap hinge and maintains it straight.

After filling the container with its intended product

75

through its open bottom end and closing same in seam forming relationship in a similar manner as hereinbefore described, the container upon reaching the consumer may be easily opened for dispensing purpose in the manner shown in FIG. 5. This is accomplished by pulling outwardly on the bottom end of the severable section 29 of the panel 17 thereby releasing it along its perforated lines 20 into open position. After dispensing a portion of the container contents, the gate section 29 may be closed in the manner illustrated in FIG. 6 and be retained in closed condition by inserting the tab 23 into the receptive slit line 16 as shown in FIG. 6. This tab thus constitutes a releasable latch that retains the re-closure in tightly restored condition in repeated dispensing sequence, independently of the adhesive securement initially established.

A modification of the container, affording a useful simplification thereof, is shown in FIG. 7. The blank 30 is similar in all respects to the blank 4 hereinbefore described, except with respect to the exterior surface of the side wall panel 6a and the foldable closure flap. The modification in the blank 30 consists in part in replacing the element 17 of FIG. 1 with an unperforated plain panel 31 extended outwardly from its base line 32, the end of the panel having a flange 33 hinged at 34. A frame-shaped pattern of adhesive material g is applied to the face of the panel 31, to ledge plies e' and f' and to side wall panel 6a. This pattern extends around three sides of the dispensing aperture 15a, transversely across the hinge line connecting the adjacent tuck (e'-f') to the side wall 6a, and along an area adjacent to and parallel to the outer edge of the closure flap 31. The pattern shown is rectangular, but this is not essential. It is important only that the pattern be of such symmetry, and so located, that it creates opposed U-shaped patterns on the closure flap and side wall when the carton is set up.

The adhesive material that may be utilized for this purpose may be in the category of latex and copolymer coatings formulated to seal only to itself by direct pressure contact, yet being adapted for the cohesive bond to be cleanly released and resealed in periodic sequence of manipulation. As shown in FIG. 7 the stripe of the adhesive g has four sides, U-shaped on the panel 6a and inverted U-shaped on the panel 31. Regardless of the protective coating material that may be utilized upon the interior surface of the blank, upon stacking multiple blanks together, the adhesive material g will not stick to such other coated or plain surfaces.

Upon folding the blank and setting up the container 35 in the manner hereinbefore described (FIG. 8) the panel 31 is folded down on its hinge line 32 whereby the matching cohesive U-shaped borders are brought into direct contact with each other thereby sealing the aperture 15 of the container. To open the container for dispensing purpose, it is merely required to lift and pull outwardly upon the free flange 33 of the panel 31, as shown in FIG. 9. After dispensing a portion of the product from the container, it may then be re-closed by simply swinging the opened panel into closed position whereby it is again cohesively sealed for continued protection of the remaining contents in the container.

In general it will be understood that numerous changes in details may be made by those skilled in the art without necessarily departing from the spirit and scope of the invention as expressed in the appended claims.

What is claimed is:

1. A carton blank of foldable material comprising hinged panels adapted to form the front, rear and side walls of the carton, one of said side walls being provided with a dispensing aperture adjacent to its end edge, panels hinged to the end edges of the said front and rear wall panels and adapted to overlie each other to form an end wall of the said carton, tuck panels secured by connecting hinges to the end

edges of said side wall panels respectively and adapted to form tucks underlying the said end wall of said carton,
 each tuck panel comprising a pair of adjacent areas hinged together along a line parallel to the connecting hinge, 5
 said areas being superposable to form a two-ply tuck, a closure flap for said dispensing aperture hingedly connected to the outer edge of the outer ply of the adjacent tuck,
 adhesive means adapted to secure said closure flap to said side wall along an area adjacent to said aperture on the side remote from said closure flap hinge, 10
 one of said end wall panels being coated on both faces with heat-activatable adhesive,
 the coating on one face serving to bond said panel to the underlying tucks when said carton is folded, the coating on the other face serving to bond said panel to the other end wall panel to provide a permanent two-layer end wall construction. 15

2. A carton blank of foldable material comprising hinged panels adapted to form the front, rear and side walls of the carton, 20
 one of said side walls being provided with a dispensing aperture adjacent to its end edge, 25
 panels hinged to the end edges of the said front and rear wall panels and adapted to overlie each other to form an end wall of the said carton,
 tuck panels secured by connecting hinges to the end edges of said side wall panels respectively and adapted to form tucks underlying the said end wall of said carton, 30
 each tuck panel comprising a pair of adjacent areas hinged together along a line parallel to the connecting hinge, 35
 said areas being superposable to form a two-ply tuck, a closure flap for said dispensing aperture hingedly connected to the outer edge of the outer ply of the adjacent tuck,
 adhesive means adapted to secure said closure flap to said side wall along an area adjacent to said aperture on the side remote from said closure flap hinge, the aperture edge adjacent to said closure flap hinge being of peaked configuration with its apex pointing toward said hinge. 40

3. A carton blank of foldable material comprising hinged panels adapted to form the front, rear and side walls of the carton, 45
 one of said side walls being provided with a dispensing aperture adjacent to its end edge, 50
 panels hinged to the end edges of the said front and rear wall panels and adapted to overlie each other to form an end wall of the said carton,
 tuck panels secured by connecting hinges to the end edges of said side wall panels respectively and adapted to form tucks underlying the said end wall of said carton, 55
 each tuck panel comprising a pair of adjacent areas hinged together along a line parallel to the connecting hinge, 60
 said areas being superposable to form a two-ply tuck, a closure flap for said dispensing aperture hingedly connected to the outer edge of the outer ply of the adjacent tuck,
 adhesive means adapted to secure said closure flap to said side wall along an area adjacent to said aperture on the side remote from said closure flap hinge, said closure flap forming part of a panel having mar-

ginal areas alongside said flap and being permanently securable to the side wall of the carton alongside said aperture,
 said flap being severable from said panel along lines of weakness between said flap and said marginal areas,
 said side wall being provided with a slit, 10
 said closure flap having a tab portion being engageable separably with said slit to hold said closure flap down independently of said adhesive securement,
 said adhesive means comprising a frame-shaped pattern of adhesive extending around three sides of said dispensing aperture, transversely across the hinge line connecting said tuck to said side wall, and along an area adjacent to and parallel to the outer edge of said closure flap,
 said pattern being so located that it creates opposed matching U-shaped patterns on said closure flap and said side wall when said carton is set up, 15
 said adhesive being of pressure-sensitive separable resealable character adhering only to itself to allow said closure flap to be repeatedly lifted and restored.
 4. A carton blank of foldable material comprising hinged panels adapted to form the front, rear and side walls of the carton, 20
 one of said side walls being provided with a dispensing aperture adjacent to its end edge, 25
 panels hinged to the end edges of the said front and rear wall panels and adapted to overlie each other to form an end wall of the said carton,
 tuck panels secured by connecting hinges to the end edges of said side wall panels respectively and adapted to form tucks underlying the said end wall of said carton, 30
 each tuck panel comprising a pair of adjacent areas hinged together along a line parallel to the connecting hinge, 35
 said areas being superposable to form a pair of marginal two-ply panel seating ledges,
 a closure flap for said dispensing aperture including an extension hingedly connected to the outer corner edge of the outer ply margin of the inner ply portion of one of said panel seating ledges,
 adhesive means adapted to secure said closure flap to said side wall along an area adjacent to said aperture on the side remote from said closure flap hinge, 40
 one of said end wall panels being coated on both faces with heat-activatable adhesive,
 the coating on one face serving to bond said panel to the underlying tucks when said carton is folded, the coating on the other face serving to bond said panel to the other end wall panel to provide a permanent two-ply end wall closure formed construction. 45
